(57) **CLAIM**

The ornamental design for drug administration safety label, as shown and described.

DESCRIPTION

FIG. 1 is a top plan view of a drug administrative safety label of our new design,

FIG. 2 is a top plan view of an alternative embodiment of a drug administrative safety label of our new design,

FIG. 3 is a top plan view of an alternative embodiment of a drug administrative safety label of our new design,

FIG. 4 is a top plan view of an alternative embodiment of a drug administrative safety label of our new design,

FIG. 5 is a top plan view of an alternative embodiment of a drug administrative safety label of our new design,

FIG. 6 is a top plan view of an alternative embodiment of a drug administrative safety label of our new design,

FIG. 7 is a top plan view of an alternative embodiment of a drug administrative safety label of our new design,

FIG. 8 is a top plan view of an alternative embodiment of a drug administrative safety label of our new design,

FIG. 9 is a top plan view of an alternative embodiment of a drug administrative safety label of our new design; and,

FIG. 10 is a top plan view of an alternative embodiment of a drug administrative safety label of our new design.

In the drawings, the broken lines represent environmental structure forming no part of the claimed design.
